TRIPLEX RECEPTACLE OUTLET

Arthur J. Pulos, Fayetteville, and Paul B. Sweeney, Jr.,
Syracuse, N.Y., assignors to Pass & Seymour, Inc.,
Syracuse, N.Y., a corporation of Delaware

Filed Apr. 11, 1966, Ser. No. 1,847

Term of patent 7 years

(Cl. D26—13)

FIG. 1

FIG. 2

FIG. 1 is a plan view of a triplex receptacle outlet showing our new design; and

FIG. 2 is a cross sectional view taken substantially along line 2—2 of FIG. 1.

The broken lines of a face plate are for illustrative purposes only. The sides not shown are substantially plane and unornamented.

We claim:

The ornamental design for a triplex receptacle outlet, as shown and described.
